UNITED STATES PATENT OFFICE.

CHARLES H. ROMEISER AND TROY R. LIVINGSTON, OF MUNCIE, INDIANA, ASSIGNEES
TO MUNCIE OIL ENGINE CO., OF MUNCIE, INDIANA, A CORPORATION.

OIL ENGINE.

Application filed May 3, 1924. Serial No. 710,726.

To all whom it may concern:

Be it known that we, CHARLES H. ROMEISER and TROY R. LIVINGSTON, citizens of the United States, and residents of Muncie, 5 county of Delaware, and State of Indiana, have invented a certain new and useful Oil Engine, and do hereby declare that the following is a full, clear, and exact description thereof, reference being had to the accompanying drawings, in which like numerals refer to like parts.

This invention pertains to an oil engine of the semi-Diesel type and has particular reference to the cylinder and igniter head 15 with their associated parts.

The object of the invention is to provide an oil engine having an igniter head so constructed and arranged as to eliminate the necessity of employing means for directing 20 or deflecting the fuel charge to the starting plug in starting the engine, and so arrange the cooling system for the igniter head that the cooling thereof may be varied in accordance with seasonable or climatic variation 25 in temperature as well as the variation in load. This is accomplished by providing a substantially conical igniter head with the fuel nozzle positioned in the apex thereof and so arranged as to discharge the fuel 30 spray conforming to the contour of the inner walls of the head, and the mounting about said igniter head a separate loose fitting and adjustable cooling jacket, for the purposes which will hereafter be more fully 35 set forth and described.

Another object of the invention resides in the convex and concave surfaces of the cylinder head, with the corresponding curved upper surface of the piston, as well 40 as the peculiarly arranged passage connecting the igniter head with the cylinder and extending through the cylinder head at an angle as will be hereinafter more specifically set forth and described. This results 45 in a more efficient combustion of the fuel and the elimination of carbon and residue resulting from poor combustion.

Other features and advantages of the invention will be more fully set forth and described in the following specifications and claims.

The full nature of this invention will be understood from the accompanying drawings and the following description and 55 claims.

Fig. 1 is a central vertical section through the upper portion of an oil engine. Fig. 2 is a plan view of the cylinder head. Fig. 3 is a central vertical section through the cylinder head. Fig. 4 is a central vertical section through a portion of the cylinder head, igniter head and igniter head cooling jacket showing the connection therein between for the passage of the cooling medium. Fig. 5 is a plan view looking down on the top of the engine.

In the drawings there is shown an oil engine including a cylinder 10 surrounded by the water jacket 11 and the outer cylinder wall 12, said cylinder enclosing therein a reciprocating piston 13 having the usual piston rings 14 and top 15 provided with a convex surface.

Mounted on the top of said cylinder and rigidly secured thereto in suitable fashion, 75 there is a cylinder head 16 having the water jacket 17 formed therein and provided with an air intake port 18 controlled by the valve 19. Said cylinder head is provided on the upper surface thereof with a dished concave surface 20 and on the lower surface thereof with a concave surface 21. The surface 21 is formed of a curvature having equal radii throughout its entire surface to the curvature of the piston top 15, so that when the piston is at its extreme upper position it will be equidistant from the cylinder head at all points.

The cylinder head is provided with a fuel passage comprising oppositely disposed ports 22 and 23 connected by an intermediate slot 24. Said ports and slots are peculiarly formed as best shown in Figs. 2 and 3, wherein the ports extend diagonally in opposite direction to each other and the connecting slot is twisted to conform thereto. This arrangement results in the provision of relatively large passage ways between the igniter and cylinder, but a very small direct passage. It will be observed that the 100 charge of fuel instead of passing directly downwardly through the connecting ports must impinge against the walls thereof and become transformed by the intense heat and high pressure into a combustible charge. 105 This prevents to a large degree the free passage of raw fuel into the cylinder with the consequent formation of carbon and residue upon the walls thereof as well as on the top of the piston.

The igniter head 25 is cone shaped, having angular flanges 26 at the base thereof that are secured to the cylinder head, and terminates at its apex in an extension 27 adapted to receive the injector nozzle 28. In the lower position of the igniter head wall there is a starting plug 29 which may be highly heated in any suitable manner.

Surrounding the igniter head and formed separately therefrom there is a loose fitting hood 30 enclosing the water jacket space 31, said space being connected to the water jacket of the cylinder head by the water pipe 32. An outward extending flange 33 is formed by the lower portion of the hood 30 and is connected thereto by the studs 34 mounted on the angular flange 26 of the igniter head and extending upwardly through the flange 33 of the hood. Said hood may be adjusted in position with respect to the igniter head by the adjusting nuts 35 which are screwed onto said stud below and above flange 33. Said nuts will permit the adjustment of hood to a position in contact with or spaced from the outer surface of the igniter head.

The piston secures its impulse from the combustion of the fuel charge injected by the nozzle 28 into the conical injection chamber of the igniter head 25, which charge passes through the peculiarly formed combustion orifices 22 and 23 and their connecting slot 24 to the cylinder 10. When the piston is on forward stroke a supply of air is admitted into the cylinder, and on return stroke this air is compressed within the cylinder by the piston and forced within the injection chamber and combustion orifices 22 and 23, as well as the small clearance space between the curved top of the piston and the correspondingly curved upper surface of the cylinder head. It will be observed that by reason of the correspondingly curved surfaces of the top of the piston and cylinder head that there will be a closer confinement of the charge of air for combustion, and the concentration thereof toward the center and into the combustion orifices and injection chamber. The fuel is injected by a suitable mechanically operated fuel pump, the duration of injection and the amount of fuel injected being automatically controlled according to the existing load by means of a governor not shown herein. The fuel injection is very rapid and occurs at practically the instant of highest compression. Before starting, external heat is applied to the igniter head 25 by any suitable means, said heated igniter head being engaged by a portion of the fuel spray which will be ignited thereby aided by the heat of compression. By reason of the conical formation of the igniter head it is not necessary to employ a deflector of any kind or any other arrange-

ment for temporarily directing the fuel spray against the plug 29. Since the shape of the spray will be in substantial accordance with the inner wall of the cylinder head, and spread outwardly in accordance therewith, that portion following along the wall in which the plug 29 is ignited with contact therewith, and an additional portion thereof will be deflected by the curved surface of the cylinder head which will also be directed against said plug. Since the shape of the spray is itself like a cone and spreads evenly throughout the injection chamber it will give a better and more thoroughly and uniformly mixed charge of air.

Although the combustion orifice is in direct pathway of the fuel spray, yet by reason of its peculiar arrangement very little of the fuel passes entirely therethrough before combustion takes place. Since the walls of the passageway obstruct the flow, and only gaseous fuel remains to pass through, since any fuel vapor spray or mist will be impinged on the wall of the passageway. This prevents the ready passage of the fuel through the opening into the cylinder where certain portions would otherwise be deflected or splashed against the relatively cool walls of the cylinder preventing proper combustion thereof. Consequently the usual carbon formation on the walls of the cylinder and the clogging of the piston rings thereby, as well as scored cylinder and piston surfaces and contamination of the lubricating oil is avoided. A further function of the oppositely and diagonally directed orifices, is to give the charge passing therethrough a twirling motion such as to produce a turbulent effect of the gas for more uniformly mixing and spreading it in the combustion chamber.

The water jacket hood 30 may be adjusted to suit seasonable or climatic conditions by varying the position of the nuts 35. Obviously by increasing the space between the hood and the igniter head a greater amount of heat may be maintained by the head, whereas on the other hand, by bringing them closer together or in contact, more heat will be carried away from the igniter head by the cooling medium. Furthermore the cooling of the head will be automatic to the extent that upon its being expanded to a high degree of heat it will be brought into closer contact with the water cooling jacket whereby excess heat will be carried away, and on the other hand where it is contracted by reason of its being relatively cool, it will be spaced further from the hood so as to maintain its accumulated heat. This is important in obtaining maximum efficiency, particularly with light loads.

From the foregoing it will be observed

that by reason of the design of the igniter head, the method of properly cooling the same, the arrangement of the curved surfaces of the cylinder head, top of the piston, and passageway through the cylinder head at the point of combustion, substantial advantages, as above mentioned, are obtained.

5 The shape of the piston is of further benefit in confining the compressed charge of air within close limits, and dispelling through the exhaust ports the solid portions of fuel that might through reason of frequent starting or from any other cause accumulate in the combustion chamber or any other 10 point. When such solid portions of fuel through some cause drop onto the convex top surface of the piston, in a vertical engine, the curvature of said surface directs such portions of fuel to the wall of the cylinder where the force of the exhaust over the 15 end of the piston will dispel them through the exhaust port. This further aids in the elimination of carbon and the accumulation of such residue on the head of the piston 20 and the cylinder walls.

25 The invention claimed is:

1. In an oil engine, the combination with a cylinder, a piston reciprocable therein and a cylinder head, of a cone shaped igniter head having a base thereon connected with the cylinder head, a fuel nozzle extending downwardly through the apex thereof, and a water jacket formed separately from said head and mounted with respect thereto so 30 as to be capable of adjustment toward and away from the external surface thereof.

2. In an oil engine, the combination with a cylinder, a piston reciprocable therein and a cylinder head, of a cone shaped igniter head having a base thereon connected with the cylinder head, a fuel nozzle extending downwardly through the apex thereof, a water jacket formed separately and independently of said head and corresponding to 40 the shape thereof so as to be capable of surrounding the greater portion of the outer surface thereof in equi-spaced relation, and means for adjustably supporting said jacket with respect to said head for varying the 45 space relation between.

50 3. In an oil engine, the combination of a

cylinder, a piston reciprocably mounted therein, and an igniter head therefor having an injection nozzle, of a cylinder head having a pair of oppositely inclined orifices 55 therein, said orifices being connected by a twisted slot for preventing the free and direct passage of fuel from said igniter head to the cylinder.

4. In an oil engine, a cylinder, a piston 60 having a convex top reciprocably mounted therein, a cylinder head mounted on said cylinder and having a concave under surface of substantially the same radius of curvature as the top of said piston, said cylinder head being provided on the top thereof with a concave curved surface, said concave surfaces being connected with angularly directed orifices oppositely disposed to each other, a conical igniter head mounted 65 on said cylinder head so that the lower portion thereof embraces the concave surface of said head, a hood for said igniter head, and means for adjustably mounting said hood on said head for varying the cooling effect 70 thereof, substantially as and for the purpose described.

5. In an oil engine, a cylinder, a piston 75 having a convex top reciprocably mounted therein, a cylinder head mounted on said cylinder and having a concave under surface of substantially the same radius of curvature as the top of said piston, said cylinder head being provided on the top thereof with a concave curved surface, said concave 80 surfaces being connected with angularly connected orifices oppositely disposed to each other, said orifices being connected by a twisted slot substantially in the center of said surfaces, a conical igniter head mounted 85 on said cylinder head so that the lower portion thereof embraces the concave surface of said head, a hood for said igniter head, and means for adjustably mounting said hood on said head for varying the cooling effect 90 thereof, substantially as and for the purpose described.

In witness whereof, we have hereunto affixed our signatures.

CHARLES H. ROMEISER.
TROY R. LIVINGSTON.
